UNITED STATES PATENT OFFICE.

JOHN G. MORITZ, OF GLASSPORT, PENNSYLVANIA.

GLASS MOLD.

Application filed May 22, 1922. Serial No. 563,057.

To all whom it may concern:

Be it known that JOHN G. MORITZ, a citizen of the United States of America, residing at Glassport, in the county of 5 Allegheny and State of Pennsylvania, has invented new and useful Improvements in Glass Molds, of which the following is a specification.

The object of the invention is to provide 10 a simple, inexpensive and efficient means whereby the handle of a glass receptacle such as a basket may be molded simultaneously and in connection with or attached to the body portion of the article and may be 15 made of any preferred design suited to that of the body of the receptacle while permitting of the opening of the mold for the removal of the article as soon as the plunger and cap or ring have been withdrawn from 20 the body portion of the mold; and with these objects in view the invention consists in a construction and combination of parts of which a preferred embodiment is shown in the accompanying drawings, wherein:—

25 Figure 1 is a side view, and

Figure 2 is a longitudinal sectional view of a mold embodying the invention.

Figure 3 is a view similar to Figure 2 showing the lifter in operation after the 30 removal of the plunger and cap or ring.

Figure 4 is a plan view of the mold body.

Figure 5 is an inverted view of the ring or cap.

Figure 6 is a transverse sectional view of 35 the mold body.

Figure 7 is a detail view of the lifter detached.

The mold body 10 mounted upon a suitable base 11 corresponds in general construction with those now in common use 40 and may be made of any desired number of relatively movable sections—that is two or more, the type selected for illustration of the invention having the main section 45 10^a and the supplemental sections 10^b hingedly connected with the main or front section by the pins 12 engaging eyes 13, and hingedly connected together and detachably connected together by the pin 14 50 engaging the eye 15. Likewise the ring or cap 16 and the plunger 17 used in connection therewith are in general features of the ordinary or conventional forms and operate as in the usual practice.

55 It will further be understood that the

mold may be made of any desired size depending upon the dimensions of the receptacle to be molded and may be adapted for producing molded articles of any preferred or desired shape or design.

Formed in the face of the mold body and in the under surface of the ring or cap are the registerable complementary grooves or channels 18 and 19 combining to form a mold for a receptacle handle, and the extremities of the channel thus provided are extended downwardly and inwardly as indicated at 18^a to break into the interior of the body portion of the mold so as to unite the extremities of the handle molded therein 60 with the body of the receptacle at points below the upper edge thereof and at any desired distance therefrom to suit the design of the article. This handle molding channel is disposed in concentric or partly surrounding relation with the opening in the body portion of the mold, substantially in the plane of the upper edge of the latter and in communication with the interior of the body portion of the mold as above indicated, so 65 that in the operation of the plunger after the seating of the ring or cap and the pouring of the molten glass or other material of which the receptacle is to be produced, the material will find its way into the handle 70 molding channel at the same time that it finds its way into the other portions of the mold to produce the design for which the mold is intended.

Also, as in the usual practice, after the 75 necessary stroke of the plunger, the latter is lifted with the ring or cap from the body portion of the mold to expose the upper end of the molded article, and with a view to providing for the opening of the body of 80 the mold to permit the removal of the molded article that feature constituting the essential part of the present invention has been designed and consists of a means for raising the molded handle out of the 85 channel in the body of the mold to assume an upwardly deflected position as indicated in Figure 3. In the illustrated embodiment of the invention this means consists of a lifter block 20 let into a recess 21^a in the 90 front section of the body of the mold and conforming in configuration with the adjacent portion of the surface or face of the mold and in effect constituting a segment 95 of the edge of the mold, together with 100 105 110

means for displacing said lifter block upwardly after the plunger and ring have been removed from the body of the mold.

Said means consist of a lever 21 pivotally mounted as at 22 in a suitable opening 23 in the front end of the mold and pivotally connected as at 24 to a stem 25 depending from the block 20. Pressure upon the exposed outer end of the lever will lift 10 the block sufficiently to raise the molded handle of the receptacle out of the channel in which it has been molded so that the sections of the mold can be separated to remove the receptacle.

15 It will be understood that the construction indicated provides for the formation of a handle, of any desired cross sectional contour or shape and also of any desired longitudinal formation, and that after the 20 removal of the receptacle from the mold or at any time subsequent thereto during the finishing of the article, the bent portions of the handle member may be reheated or straightened or given any desired form in 25 accordance with the design contemplated for the completed article.

In order to permit of relative sliding movement of the sections of the mold body the front mold section 10^a is provided with 30 a depending lug 26 engaging a slot 27 in the base, so that after the withdrawal of the plunger and ring or cap and the operation of the lifter to displace or deflect the handle member of the molded receptacle, the front 35 section of the mold body can be moved away from the other section thereof upon the disengagement of the hinge pins by which the sections are connected.

Having described the invention, what is 40 claimed as new and useful is:—

1. A molding apparatus of the type indicated having a section or mold body and

a ring or cap provided in their contact faces with complementary registering channels combining to form a handle mold in 45 communication with the interior of the receptacle mold, and means for upwardly deflecting the molded handle after the completion of the molding operation and consisting of a lifter block movable with relation to and carried by one of the mold sections.

2. A molding apparatus of the type indicated having a section or mold body and a ring or cap provided in their contact 55 faces with complementary registering channels combining to form a handle mold in communication with the interior of the receptacle mold, and means for upwardly deflecting the molded handle after the completion of the molding operation and consisting of a lifter block constituting a segment of one of the mold sections including a portion of the handle molding element thereof, mounted for movement in a direction at an angle to the plane of the face of the mold.

3. A molding apparatus of the type indicated having a section or mold body and a ring or cap provided in their contact faces 70 with complementary registering channels combining to form a handle mold in communication with the interior of the receptacle mold, and means for upwardly deflecting the molded handle after the completion 75 of the molding operation and consisting of a lifter block let into the face of one of the mold body sections and a terminally exposed actuating lever for imparting movement thereto.

In testimony whereof he affixes his signature.

JOHN G. MORITZ.
